UNITED STATES PATENT OFFICE.

CHARLES J. SUSSMAN, OF NEW YORK, N. Y.

ASH-CAN.

No. 867,683.

Specification of Letters Patent.

Patented Oct. 8, 1907.

Application filed March 14, 1907. Serial No. 362,335.

To all whom it may concern:

Be it known that I, CHARLES J. SUSSMAN, a citizen of the United States, residing at the borough of Brooklyn, in the county of Kings, city and State of New York, have invented an Improvement in Ash-Cans, of which the following is a specification.

My invention relates to an improvement in metallic ash cans, with the object of lessening the weight and increasing the stiffness and rigidity of such articles.

10 In carrying out my invention, my improved ash can comprises a cylindrical sheet metal body with circumferential stiffening metal bands or hoops at the respective ends secured exteriorly thereto, and this body is longitudinally and circumferentially stiffened, made 15 rigid and protected by series of reverse curve bands laid edgewise to the can and flatwise together, the same being riveted together at adjacent or meeting surfaces so as to produce a metallic net work around the can of substantially circular and semi-circular figures, the 20 respective ends of said bands being overturned against the surfaces of the end ribs and riveted in place thereto.

In the drawing, Figure 1 is an elevation and partial section representing the device of my improvement. Fig. 2 is a plan of the same. Fig. 3 is a sectional plan 25 at the dotted line x, x . Fig. 4 is a vertical section at the dotted line y, y , of Fig. 1; and Fig. 5 is a front elevation of the parts shown in Fig. 4, Figs. 3, 4 and 5 being of the same size but of exaggerated proportions over Figs. 1 and 2.

30 The sheet metal body a is cylindrical and the bottom of the can a^1 is preferably made with a flange so as to be secured within and at one end of the sheet metal body a .

b c are the circumferential end bands or hoops placed exteriorly of the body a and secured thereto by rivets 35 or in any desired manner.

An ash can of metal constructed with a cylindrical sheet metal body, a metal bottom portion flanged as described and external end bands is not new, *per se*, but such sheet metal cans lack strength and are very 40 liable to be dented or otherwise damaged in use. To such a can I impart strength and rigidity and the essential features of my invention consist in the series of reverse curve bands d which are laid edge-wise to the can and flatwise together around exteriorly of the can.

45 These are connected by the rivets 2 at the meeting faces of the curves and the respective ends of said bands d are over-turned and out-turned as at d^1 and are secured by the rivets 3 4 to the end bands or hoops b c . The drawings are believed to show clearly how the free

50 ends of the bands d are over-turned and out-turned, the over-turned ends being against the band itself and the out-turned substantially at right angles thereto so as to produce flat portions adapted to lie against the surfaces

of the bands b c and through which holes are provided for the rivets 3 4. A metallic net work is thus produced 55 around the can of substantially circular and semi-circular figures protecting the sheet metal body in all ordinary cases from contact with fixed points which would dent or injure or perforate the same, and while this net work of bands thus protects the sheet metal 60 body it produces a circumferential rigidity and stiffness and also a longitudinal rigidity and stiffness strengthening and making more firm the can in both directions.

I have shown handles in Fig. 1 secured upon opposite sides of the can; these are of ordinary character 65 such as are usually employed and do not require further description.

I claim as my invention:

1. A metallic can for ashes etc., comprising a sheet metal body, circumferential metal hoops at the ends thereof and a series of reverse curved bands laid edgewise to the can and flatwise together extending circumferentially of the body, means for connecting together the adjacent meeting faces of the series of bands, the free ends of each of said bands being carried over the surface of the said 70 hoops overturned against themselves, and outturned against the said hoops, and means for connecting the outturned ends of the said bands to the said hoops.

2. A metallic can for ashes, etc., comprising a sheet metal body, circumferential hoops at each end thereof, and 80 a series of bands laid edgewise to the body and flatwise together, each of the said bands being independently secured at its ends to the said hoops and connected to each of the next adjacent bands intermediately of the said hoops to 75 form a net work around the said can.

3. A metallic can for ashes, etc., comprising a sheet metal body, circumferential hoops at each end thereof, a series of bands laid edgewise to the body and flatwise together, each of the said bands being secured at its ends to the said hoops and to each of the next adjacent bands intermediately of the said hoops to form a net work around the said can, the ends of each of the said bands being carried over the surface of the said hoops, overturned against themselves, and outturned to lie against the surface of the bands, and means for connecting the ends of each band to 90 the said hoops independently of any of the other bands.

4. A metal can for ashes, etc., comprising a sheet metal body and sheet metal bottom, circumferential metal bands or hoops placed exteriorly to the can at the respective ends thereof and secured to the body, a series of reverse curve 100 bands laid edge-wise to the can and flatwise together, extending circumferentially of the body and also lengthwise of the same, rivets connecting together the adjacent meeting faces of the series of bands so as to produce a metallic net work, the bands being of reverse curve so as to produce substantially circular and semi-circular figures, the free ends of said bands being over-turned against the bands and out-turned and perforated to lie against the outer surface of the end bands, and rivets connecting the same in place thereto.

Signed by me this sixth day of February 1907.

CHARLES J. SUSSMAN.
